UNITED STATES PATENT OFFICE.

NEWTON C. SCHELLINGER, OF SALT LAKE CITY, UTAH.

AUTOMATIC FIREARM.

1,029,720.

Specification of Letters Patent. Patented June 18, 1912.

Application filed June 25, 1908. Serial No. 440,290.

To all whom it may concern:

Be it known that I, NEWTON C. SCHELLINGER, a citizen of the United States, residing at Salt Lake City, in the county of Salt Lake and State of Utah, have invented certain new and useful Improvements in Automatic Firearms, of which the following is a full, clear, and exact description, reference being had to the accompanying 10 drawings, forming a part of this specification.

My invention relates to automatic firearms of the type in which the ejector, the hammer-cocking mechanism, and the mechanism for feeding a fresh cartridge to the firing chamber are automatically operated, due to the forces incident to the discharge of the arm. In a firearm of this character it is absolutely essential that some means 20 shall be provided to keep the breech of the gun closed after discharge, or substantially so, for a sufficient time to permit the pressure of the powder gases in the barrel to be reduced below the danger point, otherwise 25 these gases would escape at the breech of the gun and do serious injury to the user of the gun.

The object of my invention is to produce a firearm whose barrel is substantially stationary during discharge and in which the position of the breech-block with respect to the gun-barrel, during a portion of the time that it takes the bullet to pass through the barrel, is controlled by positively acting 35 mechanism, either to lock the breech-block to the barrel during this time or to allow of a gradual movement of the breech-block away from the barrel. To accomplish this result I provide a locking member adapted 40 to engage the breech-block, the engagement between these two parts being such that it can be overcome by sufficient force exerted on the breech-block. But this locking member is connected with the barrel in such a 45 manner that the inertia of the barrel and its tendency to move forward with the bullet, due to the friction of the bullet on the barrel, holds the locking member in engagement with the breech-block with such force as to 50 prevent its being overcome by the pressure which the powder gases exert on the breech-block tending to drive it to the rear. After the bullet has traversed a portion of the barrel's length its drag on the barrel materially decreases or ceases and the pressure

of the powder gases is sufficient at this time to overcome the engagement between the locking member and the breech-block and drives the breech-block to the rear of the receiver to extract and eject the cartridge, 60 cock the hammer and compress the reaction spring, which in turn returns the breech-block to its normal firing position.

I have illustrated my invention in two different embodiments. 65

Figure 1 illustrates in side elevation a rifle constructed in accordance with my invention. Fig. 2 is a vertical longitudinal sectional view of the breech part of the arm. Fig. 3 is a partial central horizontal longitudinal section view taken on line 3-3 of Fig. 2. Fig. 4 is a view in side elevation of the breech-block and the locking lever of the embodiment illustrated in Fig. 2. Fig. 5 is a bottom view of the locking lever of Fig. 2, the fore-stock being removed to reveal the construction of the locking lever. Fig. 6 is a cross-sectional view taken on the line 6-6 of Fig. 2. Fig. 7 is a cross-sectional view taken on lines 7-7 of Fig. 2. Fig. 8 shows, in a longitudinal vertical sectional view, the essential mechanism of another embodiment of the breech-block and locking mechanism. Fig. 9 is a partial horizontal longitudinal section view on line 9-9 of Fig. 8. Fig. 10 is a cross-sectional view of the breech-block mechanism, taken on line 10-10 of Fig. 8. Fig. 11 illustrates, in longitudinal section, a modification of the fore end of the gun-barrel. 70 75 80 85 90

Referring first to the form of my invention illustrated in Figs. 1, 2, etc., the butt stock is shown at 11, the gun frame at 12, the fore stock at 13, the receiver at 14, and the barrel at 15. It will be noted that the receiver extends forwardly some distance around the gun-barrel, this part of the receiver being bored to receive the cylindrical gun-barrel. The barrel is fitted to slide easily within the tubular extension 16 of the receiver. The frame provides ways 17 upon which the feet 18 of the breech-block 19 may ride. The breech-block is fitted also to the top of the receiver, so that the breech-block is well guided and supported in its forward movement to be described. At its forward end the breech-block is provided with hooks or catches 20-20, one on either side of a heavy tongue 21 which is formed integrally with the receiver shell. These hooks 110

or catches on the breech-block coöperate with catches 22—22 upon the rearward arms of the locking lever 23, this lever being pivoted at 24 to the tongue 21. The abutment 5 piece 25, depending from the gun-barrel and preferably formed integrally therewith, is provided with surfaces concentric with respect to the pivot upon which the locking lever 23 swings. At 26 the locking lever is 10 provided with an opening to receive the abutment piece 25. The fit of the abutment piece in the opening 26 is a loose one, so that under normal conditions the locking lever is 15 free to swing. The latching spring 27 exerts a downward pressure upon the forward end of the locking lever, thereby maintaining the engagement of the hooks or latches 22 with those of the breech-block. The pressure of the spring is only a slight one, and 20 the engaging surfaces of the catches 20 and 22 are so inclined that no very great rearward force need be exerted against the breech-block to cause the rearward end of the locking lever 23 to be depressed, thus 25 unlocking the breech-block and leaving it free to traverse the receiver shell. As will be more fully explained, it is the forward pressure of the gun-barrel by way of the abutment piece 25 against the front end of the 30 opening 26 through the locking lever that causes the locking lever to be maintained in the locking position, as shown in Fig. 2, while the bullet travels through the gun-barrel. In other words, the frictional engagement of the abutment piece against the 35 forward end of the lever is sufficient to prevent the backward pressure of the breech-block from disengaging the catches of the locking mechanism. The pitman 28 is pivoted to the breech-block at 29 and connects with the socketed plunger end 30 of the reaction spring 31. The reaction spring is contained in a metal casing 32, indicated in dotted lines in Fig. 1, this casing extending 40 down into the butt stock, as shown. When the breech-block moves to the rear the reaction spring is compressed and returns the breech-block to its forward position, as 45 shown in Fig. 2, after a discharge. The hammer 35 is pivoted to the gun frame at 36, and carries a hardened roller 37 against which the hammer spring 38 may act. The trigger 37' is pivoted to the frame at 39, and a light spring 40 serves to return the trigger 50 to its normal position, as shown in the drawings. The magazine box 41 contains the cartridges, which are fed to the top of the box by a follow-up spring, not shown, in the well known manner. The breech-block 55 is provided with a depending rib 42 which engages the cartridges upon the forward stroke of the breech-block and carries them from the magazine into the chamber of the gun-barrel, one such cartridge being indicated at 43. The breech-block is provided

with a firing pin 44, the head 45 of which is struck by the hammer 35 when released by the trigger 37'.

The operation of the rifle will be apparent from this description. The parts being in the normal position shown in Fig. 2 the cartridge is exploded when the hammer is released by the trigger, this release serving to drive the end of the firing pin into the primer of the cartridge. The discharge of the cartridge sends the bullet forward through the barrel. The catches 22 of the latching member 23 normally engage the catches 20 of the breech-block extensions, but in such a manner that the backward pressure of the shell against the breech-block, due to the expanding powder gases, could overcome this engagement were it not for the fact that the friction of the bullet against the sides of the gun-barrel causes a forward pressure of the abutment 25 against the forward end of the lever 23 sufficient to prevent the backward pressure of the breech-block from overcoming the locking which is effected by the catches 20—22. The result is that the breech-block will be retained in its forward position in engagement with the rear end of the gun-barrel until the force of the forward drag of the bullet on the barrel falls to such a point that the pressure which the gases are exerting on the shell and breech-block overcomes the locking engagement. When the forward pressure of the gun-barrel will no longer serve to act upon the forward end of the locking lever to retain it in the normal position shown in the drawings, the breech-block will disengage itself from the locking member and will be forced rapidly to the rear end of the receiver, due to the backward pressure of the rapidly expanding gases which act against the shell. During the backward stroke of the breech-block, the extractor 45 withdraws the empty shell from the firing chamber, whereupon the nose 46 of the extractor 47 strikes the end of the shell to throw it out of the receiver through the opening 48. During the backward stroke of the breech-block the pitman connecting with the reaction spring causes the compression of this spring until the breech-block reaches the rear end of the receiver. The reaction spring then serves rapidly to return the breech-block to the forward end of the receiver. In so doing, the projection upon the lower side of the breech-block engages a shell which has been fed to the top of the magazine box, whereupon a fresh cartridge is fed to the chamber as the breech-block comes home to the position shown in Fig. 2 of the drawings. This operation takes place automatically with each discharge of the firearm, so that it is merely necessary for the operator to actuate the trigger.

I have not encumbered the drawings nor

description with any of the safety appliances and attachments which might be incorporated into an embodiment of my invention. The use of such devices is well understood, however, and they may be incorporated into an embodiment of my invention by those skilled in the art.

It will be seen that my invention provides a means for securing an effective locking 10 of the breech-block to the barrel during the discharge of the firearm.

It will be apparent that it is not essential to this embodiment of my invention that the gun-barrel should have more than 15 the very slightest degree of movement in the gun frame or receiver.

In the embodiment of the invention illustrated in Figs. 8, 9 and 10, the mechanism is substantially the same as that already 20 described except in the following particulars. The locking member 50 is pivoted at 51 to the gun-barrel and is fulcrumed on the frame by means of the interengaging teeth illustrated at 54-55. The locking member 25 engages at its rear end 56 with a projection upon the lower side of the breech-block 57. The front side of the locking member, which is presented to view in Fig. 8, is cut away to permit the ejection of the empty shells. 30 The other side of the locking member is formed as indicated in the dotted line at 58, thus giving sufficient strength to lock the breech-block firmly to the butt end of the barrel. In this embodiment of my invention 35 the barrel has a definite, though very slight, longitudinal movement, and in its normal firing position, as indicated in Fig. 8, the barrel is at the forward limit of its movement. When the cartridge is exploded 40 the rapidly expanding gases cause a backward pressure to be exerted against the breech-block and a forward pressure against the bullet. This rearward pressure will not, however, serve to unlock the breech for the 45 reason that the inertia of the barrel and its tendency to move forward with the bullet, due to the frictional engagement of the bullet on the sides of the barrel, holds the barrel in its normal firing position and so holds 50 the locking lever firmly in contact with the rear end of the breech-block. When the bullet has traversed a portion of the barrel's length to a point where the influence of the bullet on the barrel tending to drag it forward 55 has been materially reduced or has ceased, the rearward pressure of the gases causes the breech-block to disengage from the locking lever, which in effect means that the breech-block depresses the rear end of 60 the locking lever, rocking it on its fulcrum, and moving the barrel slightly to the rear. The initial impulse given to the breech-block by the gases gives it sufficient momentum to carry it to the rear of the receiver as soon 65 as it is released from the locking lever, ex-

tracting and ejecting the cartridge, cocking the hammer, and compressing the reaction spring which then throws the breech-block forward to its normal firing position during which movement a new cartridge is fed into 70 the firing chamber.

It will be understood that in both embodiments of my invention the angle of inclination of the engaging surfaces on the locking member and the breech-block must be 75 laid out in relation to other parts of the gun in order that the balance and proper operation of the gun may at all times be insured.

Another detail which I have illustrated in the embodiment of Fig. 8, which however 80 does not affect the broad principle of operation of my gun, is the buffer-spring 60 and buffer 61, which aid in the sudden reversal of the direction of motion of the breech-block after discharge and serve also to relieve the shock which might sometimes occur 85 due to the breech-block striking the rear end of the receiver. I have also shown in this figure a spring-actuated toe 62 on the breech-block for engaging the cartridges in 90 the magazine and carrying them forward into the firing chamber of the gun-barrel.

At the moment of discharge the pressure of the powder gases rises very sharply to maximum and as the bullet commences to 95 move through the barrel the pressure gradually drops. The first effect of this pressure on the bullet is to spread it and drive it into the rifling; then as the bullet traverses the barrel and the pressure drops the 100 spreading effect ceases and the bullet obtains a free spinning fit in the barrel. The forward drag of the bullet on the barrel is greatest, of course, when the bullet is being sized, and is much less after the bullet has 105 ceased spreading and reached the point where it has a free spinning fit in the barrel.

In the gun of the pistol type where the barrel is short it is sometimes desirable to surely relieve the drag of the bullet on the 110 barrel before the bullet leaves the barrel and I do this by removing the rifling near the muzzle of the barrel, as indicated in Fig. 11, where the rifling is seen to stop at 71, leaving the smooth bore 72 at the end of the 115 barrel.

If it is desired to permit a gradual opening of the breech, commencing just after the ignition, it can be done by changing the angles of inclination of the locking faces on 120 the locking member and the breech-block, making them less abrupt. By this arrangement the barrel, influenced by the bullet traveling through it, holds the locking faces in engagement with sufficient force to cause 125 them to act as a brake, retarding the movement of the breech-block. The angles of inclination of the engaging faces can be calculated to exert any retarding effect which is desired and in this way a definite and 130

known controlling force can be exerted on the movement of the breech-block.

I have illustrated and described two ways of building a gun to operate in accordance with my invention. I do not, however, desire to be understood as limiting myself to the precise arrangements herein shown as I am well aware that the invention is susceptible of a variety of embodiments, and 10 believing that I am the first to produce a practical operative gun in which the locking of the breech to the barrel during discharge is controlled by the influence which the bullet exerts on the barrel, I desire to include herein and in the accompanying claims any and all modifications in which my invention is or may be embodied.

What I claim as new and desire to secure by Letters Patent of the United States is:

20 1. In a firearm, the combination of a barrel, a breech-block, a frame supporting the breech-block and barrel, and a locking member mounted on the frame and connected with and acted upon by barrel and breech-block.

25 2. In a firearm, the combination of a barrel, a breech-block, a frame in which the breech-block is slidably mounted, a locking member fulcrumed upon the frame and 30 adapted when in its normal position to lock the breech-block to the barrel, and means whereby the forward pressure of the barrel during discharge acts upon the locking member to maintain the breech-block in its 35 normal position.

30 3. In a firearm, the combination of a non-rotatable barrel, a breech-block, and means controlled by the forward pressure of the barrel during discharge to lock the breech-block to the barrel.

35 4. In a firearm, the combination of a non-rotatable barrel, a reciprocating breech-block, and means controlled by the forward pressure of the barrel during discharge to lock the breech-block to the barrel.

40 5. In a firearm, the combination of a barrel, a breech-block, a frame in which both barrel and breech-block are slidably mounted, and a locking member fulcrumed upon 45 the frame and connected with the barrel, said breech-block being locked in the firing position by the locking member when in its normal position, the disposition of the points of connection with the locking member being such that the forward pressure of the barrel acts during the traverse of the bullet through the barrel to maintain the locking member in normal position in opposition to the 55 backward pressure of the breech-block.

60 6. In a firearm, a barrel, a breech-closing member, and a locking member, said locking member serving when in its normal position to lock the breech-closing member in 65 the firing position, the forward pressure of

the barrel during discharge serving to maintain the locking member in its normal position in opposition to the pressure of the breech-closing member tending to open the breech.

70 7. In a firearm, the combination of a barrel, a breech-block, means controlled by the forward pressure of the barrel during discharge to lock the breech-block to the barrel, and a reaction spring acting upon the 75 breech-block to return it to the firing position.

8. In a firearm, the combination of a barrel, means for closing the breech, means controlled by the forward pressure of the gun barrel during discharge for maintaining the breech in closed condition during discharge, the breech-block being released upon a diminution in the forward pressure of the barrel, and a reaction spring acting upon the 80 breech-block to return it to the firing position after recoil.

9. In a firearm, the combination of a barrel, a breech-block, a frame supporting the breech-block and barrel, a locking member 90 mounted on the frame and connected with and acted upon by barrel and breech-block, and a reaction spring tending to close the breech.

95 10. In a firearm, the combination of a barrel, a breech-block, a frame in which the breech-block is slidably mounted, a locking member fulcrumed upon the frame and adapted when in its normal position to lock the breech-block to the barrel, means whereby the forward pressure of the barrel during discharge acts upon the locking member to maintain the breech-block in its normal position, and a reaction spring acting upon the breech-block and frame and tending 100 to return the breech-block to its normal position.

105 11. In a firearm, the combination of a barrel, a breech-block, a frame in which both barrel and breech-block are slidably mounted, a locking member fulcrumed upon the frame and connected with the barrel, said breech-block being locked in the firing position by the locking member when in its normal position, the disposition of the points 110 of connection with the locking member being such that the forward pressure of the barrel acts during the traverse of the bullet through the barrel to maintain the locking member in normal position in opposition to the 115 backward pressure of the breech-block, and a reaction spring tending to return the breech-block to the firing position when forced therefrom.

12. In a firearm, a barrel, a breech-closing member and a locking member, said locking member serving when in one position to lock the breech-closing member in the firing position, the forward pressure of the barrel during discharge serving to main- 125 130

tain the locking member in its normal position in opposition to the pressure of the breech-closing member tending to open the breech, and spring mechanism tending to close the breech.

5 13. In a firearm, the combination of a barrel, a breech-block, means controlled by the forward pressure of the barrel during discharge to lock the breech-block to the barrel, said breech-block being released for recoil upon the diminution of the forward pressure of the barrel, extractor, ejector, and hammer cocking and magazine-feeding mechanism automatically actuated during the recoil and return of the breech-block to the firing position.

10 14. In a firearm, the combination of a barrel, means for closing the breech, means controlled by the forward pressure of the gun barrel during discharge for maintaining the breech in closed condition during discharge, shell extracting and ejecting mechanism, cocking mechanism, and magazine-feeding mechanism, all automatically actuated upon the opening and closing of the breech.

15 15. In a firearm, the combination of a barrel, a breech-block, a frame in which the breech-block is slidably mounted, a locking member fulcrumed upon the frame and adapted when in its normal position to lock the breech-block to the barrel, means whereby the forward pressure of the barrel during discharge acts upon the locking member to maintain the breech-block in its normal position, extracting and ejecting mechanism, cocking mechanism, and cartridge-feeding mechanism, all automatically actuated by the movement of the breech-block in the frame.

20 16. In a firearm, the combination of a barrel, a breech-block, a frame in which both barrel and breech-block are slidably mounted, a locking member fulcrumed upon the frame and connected with the barrel, said breech-block being locked in the firing position by the locking member when in its normal position, the disposition of the points of connection with the locking member being such that the forward pressure of the barrel acts during the traverse of the bullet through a portion of the length of the barrel to maintain the locking member in normal position in opposition to the backward pressure of the breech-block, extracting and ejecting mechanism, cocking mechanism, and cartridge-feeding mechanism, all automatically actuated by the breech-block when released by the locking member.

25 17. In a firearm, the combination of a barrel, a breech-block, means controlled by the forward pressure of the barrel during discharge to lock the breech-block to the barrel, a reaction spring acting upon the breech-block to return it to the firing position, extracting and ejecting mechanism, cocking

mechanism, and feeding mechanism, all automatically actuated by the movement of the breech-block from and to the firing position.

30 18. In a firearm, the combination of a barrel, means for closing the breech, means controlled by the forward pressure of the gun barrel during discharge for maintaining the breech in closed condition during discharge, the breech-block being released upon a diminution in the forward pressure of the barrel, 70 a reaction spring acting upon the breech-block to return it to the firing position after recoil, extracting and ejecting mechanism, cocking mechanism and cartridge-feeding mechanism, all automatically actuated during the recoil and return of the breech-block to the firing position.

35 19. In a firearm, the combination of a barrel, a breech-block, a frame in which the breech-block is slidably mounted, a locking member 85 fulcrumed upon the frame and adapted when in its normal position to lock the breech-block to the barrel, means whereby the forward pressure of the barrel during discharge acts upon the locking member to 90 maintain the breech-block in its normal position, a reaction spring acting upon the breech-block and frame and tending to return the breech-block to its normal position, extracting and ejecting mechanism, 95 cocking mechanism and cartridge-feeding mechanism, all automatically actuated upon the movement of the breech-block.

40 20. In a firearm, the combination of a barrel, a breech-block, a frame and receiver in 100 which the barrel and the breech-block are slidably mounted, and a locking lever having a rack and pinion connection with the frame and a pivotal connection with the gun barrel, said locking lever serving when in 105 its normal position to lock the breech-block in the firing position, the leverages and angles of engagement being such that the forward pressure of the barrel during the traverse of the bullet through a portion of 110 the barrel's length maintains the locking lever in its normal position against the backward pressure of the cartridge shell upon the breech-block.

45 21. In a firearm, the combination of a barrel, a breech-block, a frame and receiver in 115 which the barrel and the breech-block are slidably mounted, a locking lever having a rack and pinion connection with the frame and a pivotal connection with the gun barrel, said locking lever serving when in its 120 normal position to lock the breech-block in the firing position, the leverages and angles of engagement being such that the forward pressure of the barrel during the traverse of the bullet through a portion of the barrel's length maintains the locking lever in its normal position against the backward pressure of the cartridge shell upon the breech-block, a helical reaction spring con- 130

nected with the frame to the rear of the breech-block, and a pitman connecting the breech-block with the end of the reaction spring.

22. In a firearm, the combination of a barrel, a breech-block, a frame and receiver in which the barrel and the breech-block are slidably mounted, a locking lever having a rack and pinion connection with the frame and a pivotal connection with the gun barrel, said locking lever serving when in its normal position to lock the breech-block in the firing position, the leverages and the angles of engagement being such that the forward pressure of the barrel during the traverse of the bullet through a portion of the barrel's length maintains the locking lever in its normal position against the backward pressure of the cartridge shell upon the breech-block, the breech-block being released upon the diminution of the friction of the discharged bullet against the sides of the barrel, extractor and ejector mechanism, cocking mechanism, and magazine-feeding mechanism, all automatically actuated by the breech-block in its movement from and to the firing position.

23. In a firearm, the combination of a barrel, a breech-block, a frame and receiver in which the barrel and the breech-block are slidably mounted, a locking lever having a rack and pinion connection with the frame and a pivotal connection with the gun barrel, said locking lever serving when in its normal position to lock the breech-block in the firing position, the leverages and the angles of engagement being such that the forward pressure of the barrel during the traverse of the bullet through a portion of the barrel's length maintains the locking lever in its normal position against the backward pressure of the cartridge shell upon the breech-block, a helical reaction spring connected with the frame to the rear of the breech-block, a pitman connecting the breech-block with the end of the reaction spring, a cartridge magazine, extracting and ejecting mechanism, hammer cocking mechanism, and mechanism for feeding cartridges from the magazine to the firing chamber of the barrel, all automatically actuated upon the backward and return movements of the breech-block.

24. In a firearm, the combination of a barrel having an outwardly flared forward end, a breech-block, a frame supporting the breech-block and barrel, and a locking member mounted on the frame and connected with and acted upon by barrel and breech-block.

25. In a firearm, the combination of a barrel having a bore enlarged at the forward end, a breech-block, a frame in which the breech-block is slidably mounted, a locking member fulcrumed upon the frame and

adapted when in its normal position to lock the breech-block to the barrel, and means whereby the forward pressure of the barrel during discharge acts upon the locking member to maintain the breech-block in its normal position.

26. In a firearm, the combination of a barrel whose bore is enlarged at the forward end, a breech-block, a frame in which both barrel and breech-block are slidably mounted, and a locking member fulcrumed upon the frame and connected with the barrel, said breech-block being locked in the firing position by the locking member when in its normal position, the disposition of the points of connection with the locking member being such that the forward pressure of the barrel acts during the traverse of the bullet through the barrel to maintain the locking member in normal position in opposition to the backward pressure of the breech-block.

27. In a firearm, the combination of a barrel rifled at the rearward end and of smooth bore at the forward end, a breech-block, a frame and receiver in which the barrel and the breech-block are slidably mounted, and a locking lever having a rack and pinion connection with the frame and a pivotal connection with the gun barrel, said locking lever serving when in its normal position to lock the breech-block in the firing position, the leverages and the angles of engagement being such that the forward pressure of the barrel during the traverse of the bullet through a portion of the barrel's length maintains the locking lever in its normal position against the backward pressure of the cartridge shell upon the breech-block.

28. In a firearm, the combination of a barrel rifled at the rearward end and of smooth bore at the forward end, said bore being enlarged at the extreme forward end of the barrel, a breech-block, a frame and receiver in which the barrel and the breech-block are slidably mounted, and a locking lever having a rack and pinion connection with the frame and a pivotal connection with the gun barrel, said locking lever serving when in its normal position to lock the breech-block in the firing position, the leverages and the angles of engagement being such that the forward pressure of the barrel during the traverse of the bullet through a portion of the barrel's length maintains the locking lever in its normal position against the backward pressure of the cartridge shell upon the breech-block.

29. In a firearm, the combination of a barrel, a breech-block, and means controlled by the forward pressure of the barrel during discharge to lock the breech-block to the barrel.

30. In a firearm, the combination of a barrel, means for closing the breech, and means controlled by the forward pressure of the

gun barrel during discharge for maintaining the breech in closed condition during discharge.

31. In a fire arm, the combination with a barrel and a breech block, of means for positively locking said breech block to said barrel during discharge, said means being unlocked by the rearward movement of the breech block before the projectile leaves the barrel.

32. In a fire arm, the combination with a barrel and breech block, of means controlled automatically upon discharge for positively locking said breech block to said barrel, said means being automatically unlocked by the rearward movement of the breech block before the projectile leaves the barrel.

33. In a fire arm, the combination with a barrel and a breech block, of means controlled by the passage of the projectile

through a portion of the barrel's length for locking said breech block to said barrel, said means being unlocked by the rearward movement of the breech block before the projectile leaves the barrel.

25

34. In a fire arm, the combination with a barrel and a breech block, of means actuated by forces developed by the engagement of the projectile and barrel after discharge for locking said breech block to said barrel, said means being unlocked by the rearward movement of the breech block before the projectile leaves the barrel.

30

In witness whereof, I hereunto subscribe my name this 23rd day of June, 1908.

N. C. SCHELLENGER.
